* cited by examiner

Primary Examiner—Elizabeth A. Albert*Assistant Examiner*—Kelley A Donnelly(74) *Attorney, Agent, or Firm*—Wood, Herron & Evans, LLP.(57) **CLAIM**

The ornamental design for a mirror, as shown and described.

DESCRIPTION

FIG. 1 is a front elevational view of a mirror showing my new design.

FIG. 2 is a rear elevational view thereof.

FIG. 3 is a right elevational view thereof, with the left elevational view thereof being a mirror image.

FIG. 4 is a top plan view thereof; and,

FIG. 5 is a bottom plan view thereof.

The broken lines in FIG. 1 show environment and form no part of the claimed design.
